US00D901492S

(12) **United States Design Patent** (10) **Patent No.:** **US D901,492 S**
Gao (45) **Date of Patent:** **** Nov. 10, 2020**

(54) **SMART BRACELET**

(71) Applicant: **Shenzhen Yawell Intelligent Technology Co., Ltd.**, Guangdong (CN)

(72) Inventor: **Jinfeng Gao**, Hubei Province (CN)

(***) Term: **15 Years**

(21) Appl. No.: **29/712,643**

(22) Filed: **Nov. 11, 2019**

(30) **Foreign Application Priority Data**

Sep. 26, 2019 (CN) 2019 3 0531153

(51) **LOC (12) Cl.** **14-02**

(52) **U.S. Cl.**

USPC **D14/344; D10/32**

(57) **CLAIM**

The ornamental design for a smart bracelet, as shown and described.

DESCRIPTION

FIG. 1 is a front perspective view of a smart bracelet, showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the figures illustrate portions of the smart bracelet that form no part of the claimed design.

1 Claim, 8 Drawing Sheets
